US0D1094715S

(12) **United States Design Patent** (10) **Patent No.:** **US D1,094,715 S**
(45) **Date of Patent:** **** Sep. 23, 2025**

(54) **INSTRUMENT FOR MEASURING
EYE-HEALTH CHARACTERISTICS**

(71) Applicant: **Zeavision LLC**, Chesterfield, MO (US)

(72) Inventor: **Joshua J. Park**, Riverside, CA (US)

(73) Assignee: **ZEAVISION LLC**, Chesterfield, MO (US)

(**) Term: **15 Years**

(21) Appl. No.: **29/936,125**

(22) Filed: **Apr. 5, 2024**

(57) **CLAIM**

The ornamental design for an instrument for measuring eye-health characteristics as shown and described.

DESCRIPTION

FIG. 1 is a first perspective view of an instrument for measuring eye-health characteristics.

FIG. 2 is a second perspective view of the instrument for measuring eye-health characteristics illustrated in FIG. 1.

FIG. 3 is a rear view of the instrument for measuring eye-health characteristics illustrated in FIG. 1.

FIG. 4 is a right side view of the instrument for measuring eye-health characteristics illustrated in FIG. 1.

FIG. 5 is a front view of the instrument for measuring eye-health characteristics illustrated in FIG. 1.

FIG. 6 is a left side view of the instrument for measuring eye-health characteristics illustrated in FIG. 1.

FIG. 7 is a top view of the instrument for measuring eye-health characteristics illustrated in FIG. 1; and,

FIG. 8 is a bottom view of the instrument for measuring eye-health characteristics illustrated in FIG. 1.

In the drawings, the broken lines are for the purpose of illustrating portions of the instrument for measuring eye-health characteristics which form no part of the claimed design.

1 Claim, 5 Drawing Sheets

Related U.S. Application Data

of application No. 17/304,274, filed on Jun. 17, 2021,
now Pat. No. 11,707,194.
